(57) **CLAIM**

The ornamental design for an LED grow light, as shown and described.

DESCRIPTION

FIG. 1 is a front, right side perspective view of an LED grow light showing our new design;

FIG. 2 is a rear, right side perspective view thereof;

FIG. 3 is a front elevation view thereof;

FIG. 4 is a rear elevation view thereof;

FIG. 5 is a left side elevation thereof;

FIG. 6 is a right side elevation thereof;

FIG. 7 is a top plan view thereof;

FIG. 8 is a bottom plan view thereof;

FIG. 9 is an enlarged view of the selected portion 9 of FIG. 1;

FIG. 10 is an enlarged view of the selected portion 10 of FIG. 1;

FIG. 11 is an enlarged view of the selected portion 11 of FIG. 1;

FIG. 12 is an enlarged view of the selected portion 12 of FIG. 2;

FIG. 13 is an enlarged view of the selected portion 13 of FIG. 5; and,

FIG. 14 is an enlarged view of the selected portion 14 of FIG. 6.

The broken lines shown in the figures depict portions of the LED grow light that form no part of the claimed design. The additional broken lines encircling the enlarged views in FIGS. 1-2, 5-6, and 9-14 are for annotative purposes only and form no part of the claim thereof. The solid lines depict claimed subject matter, while the broken lines segments adjacent the solid lines depict unclaimed subject matter.

1 Claim, 13 Drawing Sheets
